DESIGN FOR A RUBBER DOILY OR
SIMILAR ARTICLE

Jacob Ernest Flaker, Barberton, Ohio

Application May 15, 1947, Serial No. 139,051

Term of patent 14 years

(Cl. D92—26)

To all whom it may concern:

Be it known that I, Jacob E. Flaker, a citizen of the United States and a resident of Barberton, in the county of Summit and State of Ohio, have invented a new, original, and ornamental Design for Rubber Doily or Similar Article, of which the following is a specification, reference being had to the accompanying drawing, forming part thereof.

In the drawing:

The figure is a plan view of a rubber doily, showing my new design, it being understood, however, that the design may be applied to similar articles without departing from the spirit of the invention.

I claim:

The ornamental design for a rubber doily or similar article, substantially as shown and described.

JACOB ERNEST FLAKER.
